UNITED STATES PATENT OFFICE.

SYLVESTER E. MCPHERSON, OF CHATTANOOGA, TENNESSEE.

ROLLER WINDOW-SCREEN.

1,143,718.

Specification of Letters Patent. Patented June 22, 1915.

Application filed July 8, 1914. Serial No. 849,812.

To all whom it may concern:

Be it known that I, SYLVESTER E. MCPHERSON, a citizen of the United States, residing at Chattanooga, in the county of 5 Hamilton and State of Tennessee, have invented new and useful Improvements in Roller Window-Screens, of which the following is a specification.

My invention relates to improvements in 10 window screens, and it provides a screen which is adapted to be a permanent fixture secured to the window frame. By permanently attaching the screen and its complementary fixtures to the frame of the window, the disadvantages attendant upon the 15 use of the usual type of window screen are eliminated.

Furthermore, the screen constructed according to my invention is of the roller type 20 thereby presenting a neat appearance to the eye either when it is in use or when it is rolled up.

Other objects of my invention are the provision of suitable side guides so that the 25 screen will always roll up in the correct manner, a suitable ending at the edge of the screen, and a suitable protective covering so as to eliminate all damage to the screen which might result from the inclemencies 30 of the weather.

Referring to the drawings annexed here- 35 to and forming a part of this specification, and in which I have illustrated one preferred embodiment of my invention:—Fig. 1 is a front elevation (outside view) showing a screen, constructed according to my invention, in position on the window frame. Fig. 2 is a side elevational view of the screen shown in Fig. 1. Fig. 3 is an end 40 view of the screen and roller in position, one of the supporting plates being removed. Fig. 4 is a front elevational view of the rollers with parts broken away to show the details thereof. Fig. 5 is an end elevational 45 view of the roller shown in Fig. 4. Fig. 6 is a sectional side plan view showing the guide attached to the casing and the screen in position.

Referring to the drawings:—Mounted on 50 the window frame 1 at the top thereof are the two members 2 and 3, said member 2 being adapted to receive the round end pin 4 of the screen roller 5, and the member 3 being adapted to receive the rectangular 55 end pin 6 of the slide screen roller. At the sides of the window frame 1 are mounted the

guide strips 7 having the circular grooved portion 8, the purpose of which will be hereinafter set forth.

The screen 9 is composed of flexible wire 60 mesh bound at the side edges with wire cord 9^a such as is used for hanging pictures which is adapted to reinforce the mesh and also adapted to run in the circular groove portions 8 of the guide strips 7. The mesh is 65 secured at the top to the screen roller 5 which is constructed similar to the ordinary curtain roll being composed of the cylindrical shell 10 to which the mesh is attached and is closed at the ends by the members 2 70 and 3, the whole being mounted on the rod 11 with which the end pins 4 and 6 are integral. Within the cylindrical shell 10 is disposed a coil spring 12 having one end 13 attached to the rod 11 and the other end 14 75 attached to the member 3 so that when the wire mesh is unwound from the said screen roll 5, the coil spring 12 will be placed under tension.

Secured to the pin 6 is a collar 15 having a 80 notch 16 therein, the said notch 16 having beveled edges and being adapted to receive the dog 17 mounted on the member 3, and which serves to stop the roller 5 in any desired position. Secured to the bottom edge 85 of the flexible wire mesh is the handle strip 18 adapted to facilitate the raising and lowering of the screen.

Mounted on the frame 1 and entirely covering the roller 5 is the curved guard 19 having its lower edge extending inwardly and beaded as shown at 20, said edge being adapted to engage the flexible wire mesh as shown in Fig. 3, and form a fly tight joint.

It will be evident from the description, 95 that the screen is fly-tight on all four sides, the bottom being provided with a handle strip 18 which engages the sill of the window, the sides being provided with the round wire cord 9^a curling in the grooves 8, 100 and the top being provided with the guard 19. It will be evident from a comparison of Figs. 2 and 6 that the cords 9^a attach to the mesh 9 in such manner that the centers of the cords are on the outside of the mesh 105 and consequently the cords take the rub when the mesh is passing over the edge of the guard 19 and so preserves the mesh from wear.

Having thus described the preferred embodiment of my invention, it is to be understood that I do not limit myself to the pre- 110

cise arrangement of parts and construction herein set forth, but may resort in practice to such modifications as fall within the scope of my claims.

5 I claim:

1. In a device of the class described in combination a window frame, a guard mounted at the upper portion of said frame, a roller mounted in said guard, wire mesh mounted on said roller and arranged to pass around the lower edge of said guard, and flexible reinforcing members secured to the edges of said mesh somewhat to one side of the plane of the mesh and on the sides toward the lower edge of said guard whereby the mesh is preserved from wear when passing over said edge.

2. A window screen adapted to be mounted on a window frame, said screen comprising in combination, a roller mounted at the top of the frame, flexible wire mesh arranged to roll on said roller, said mesh being arranged to close the window aperture when

unrolled, reinforcing lengths of wire cord secured to the sides of said mesh, guide members mounted on said frame and projecting inwardly therefrom to receive said lengths of rope, said members inclosing said lengths of rope closely but permitting the same to move freely therein, and a curved guard partially surrounding said roller and protecting the exterior thereof, said guard having a bead at its lower edge over which said mesh and said lengths of rope run, said edge being substantially in alinement with said guide members, said length of cord being bound to said wire mesh in such manner as to contact with the edge of said guard and preserve said mesh from wear.

In testimony whereof I affix my signature in the presence of two witnesses.

SYLVESTER E. McPHERSON.
